(57) **CLAIM**

The ornamental design for a selectorized dumbbell having a kettlebell style handle, as shown and described.

DESCRIPTION

FIG. 1 is a perspective view of a selectorized dumbbell having kettlebell style handle showing our new design;

FIG. 2 is a front elevational view of the design illustrated in FIG. 1;

FIG. 3 is a left elevational view of the design illustrated in FIG. 1;

FIG. 4 is a right elevational view of the design illustrated in FIG. 1;

FIG. 5 is a back elevational view of the design illustrated in FIG. 1; and,

FIG. 6 is a top plan view of the design illustrated in FIG. 1.
